INSERTED BLADE CUTTER

Frank P. Miller, Meadville, Pa.

Application April 19, 1935, Serial No. 17,359

2 Claims. (Cl. 29—105)

This invention relates to inserted blade cutters, and will be found to be in the nature of an improvement on the construction shown in my prior Patent No. 1,719,337, issued July 2, 1929.

In my prior patent herein mentioned, and more particularly in that form of invention shown on sheet 2 of the drawing therein, each inserted blade is engaged at one side thereof by a holding wedge and the wedge is, in turn, engaged at the base thereof by a tapered key which, when driven endwise, exerts an outward force on the wedge and brings about binding engagement of the wedge with the associated blade. However, in my prior patent, the wedge has a radial dimension substantially less than the radial dimension of the blade with the result that the wedge has pressure contact with but a minor portion of the blade. By reason of the position and the inferior radial dimension of the wedge, as compared to the radial dimension of the blade, the wedge actuating key is located between the inner and outer edges of the blade and at all positions of blade adjustment the blade remains in restraining relation with the key, holding the key in direct supporting engagement with the wedge and against lateral shifting into the blade receiving slot.

Also, in my prior patent herein referred to, the amount of radial blade adjustment is limited because if the blade is moved out beyond the key, the blade loses restraining relation to the key allowing the key to shift out of supporting engagement with the wedge. For this reason, the amount of blade material that may be used is limited and one of the features of this invention will be found to reside in the means by which the blade may be moved radially outward beyond the key without risking the shifting of the key out of supporting engagement with the wedge, thus allowing a maximum use of the expensive metal from which the blade is made.

However, there are cases where the wedge has a radial dimension approaching the corresponding dimension of the blade and where the blade is adjustable to a position where it is no longer in restraining relation to the associated key, with the result that the conditions accompanying the use of the tool may cause shifting or slipping of the key out of supporting engagement with the wedge, in which event the use of the cutter must be interrupted for the resetting of the blade.

With an appreciation of the foregoing, the invention forming the subject of this application will be found to be in the nature of an inserted

blade cutter in which the binding wedge located at one side of the associated blade has a radial dimension approaching the radial dimension of the blade to provide a generous area of contact between these parts causing the tapered wedge engaging key to occupy a position where, as a result of repeated adjustment of the blade to compensate for wear and grinding, the blade no longer has restraining relation to the key and in which the body of the cutter is formed with a shallow groove defining a restraining shoulder holding the key in constant supporting relation to the wedge against the contrary influences incident to use of a tool of this character.

Another object of the invention is to provide an inserted blade cutter of the type described which is of highly simplified construction, rugged and relatively cheap to manufacture.

Other objects and advantages will be apparent during the course of the following description.

In the accompanying drawing, forming a part of this application and in which like numerals are employed to designate like parts throughout the same,

Figure 1 is a fragmentary side elevation of an inserted blade cutter embodying the invention.

Figure 2 is a fragmentary group perspective of a cutting tool embodying the invention.

Figure 3 is a perspective of a wedge embodied in the tool.

Figure 4 is a sectional view taken on line 4—4 of Figure 1.

Figure 5 is a view similar to Figure 4, with the blade advanced to compensate for wear and grinding.

Figure 6 is a detail transverse view taken on line 6—6 of Figure 5.

In the drawing, wherein for the purpose of illustration is shown a preferred embodiment of the invention, the numeral 5 generally designates a carrier body. While the body is shown to be of the type employed in rotary cutters, it is clear, of course, that the invention may be carried out in other cutters. Among these might be numbered reamers, counterbores, and broaches, in all of which my invention may be incorporated without inventive adaptation.

The body 5 is shown to be provided with a plurality of spaced slots 10, opening out through the periphery and ends of the body for the adjustable reception of blades 12.

By reference to Figure 2, it will be seen that one side wall of each slot and the opposed side wall of the associated blade are formed with interfitting serrations 14 defining an adjusting

means and assisting in holding the blade more rigidly in a set position.

Of course, it is the back wall of each blade that is serrated while the front wall of the 5 blade is engaged by a wedge 16. As shown in Figures 1 and 2, the wedge 16 is tapered radially outward and is confined between the flat front surface or wall of the blade and the converging front wall of the slot with the result that outward 10 movement of the wedge will force the blade laterally into binding engagement with the back wall of the slot holding the blade securely against shifting.

It is further illustrated in Figure 1, that the 15 wedge 16 has a radial dimension approaching the corresponding dimension of the blade as initially present in the tool, producing a generous area of contact between these parts and at the same time causing the base of the wedge to be 20 positioned close to the inner edge of the blade as originally positioned in the tool.

Each wedge is shown to be engaged at the inner edge thereof by a longitudinally tapered key 18 driven into place from one end or side of 25 the tool and functioning as a means to force the wedge outwardly for cooperation with the inclined front wall of the slot in forcing the wedge laterally into firm binding engagement with the complementary blade. Initially, the key 18 is 30 overlapped by the inner portion of the associated blade and is thus held against lateral shifting by the blade but by reference to Figure 5, it will be seen that as a result of repeated adjustment of the blade to compensate for wear 35 and grinding, the blade passes out of range of the tapered key and no longer has restraining relation thereto.

To provide for the constant holding of the key against lateral shifting regardless of the position 40 of the associated blade, the bottom of the blade and wedge receiving slot will be found to be stepped to define a shoulder 34 in constant restraining relation to the key. That is to say, the bottom of the blade and wedge receiving slot 45 is stepped downward between the sides thereof so as to define a right angle shoulder at one side of and in direct restraining relation to the tapered key for the full length of said key and so as to maintain the key in constant supporting 50 and bracing relation to the associated wedge against the contrary influences known to accompany the use of tools of this type.

By reference to Figures 1 and 6 it will be seen that the inner portion of the leading side wall 55 of the slot 10 is parallel or substantially parallel to the back side wall of the slot while the inclined portion of such leading side wall of the slot is beyond the range of the key. By this arrangement, the key is constantly spaced from the 60 inclined portion of the leading side wall of the slot and consequently is allowed to have full and undisturbed contact with the wedge and is not forced laterally by the converging portion of the side wall of the slot.

65 The break in the leading side wall of the slot will be found to hold down the lateral dimension of the slot at the base portion thereof and thus avoids weakening of the body.

Figures 1, 3 and 4 illustrate that one side wall 70 of the wedge 16 is formed at what might be said to be the forward and inner corner portion thereof with a triangular relief 25 by which the wedge is constantly spaced, in all operative positions thereof, from the radial inner portion of 75 the opposed side wall of the slot. That is to say,

the triangular relief 25 avoids contact between the inner corner of the wedge 16 and the radial or base portion of the opposed wall of the slot.

An inserted blade tool embodying the invention disclosed herein marks a definite advance over the showing in my prior patent herein identified, in that the key 18 is held in constant supporting relation to the associated wedge by the presence of the shoulder 34 while there is allowed a generous area of contact between the wedge and the blade, these matters being in contrast to the rather limited or restricted area of contact between the wedge and the blade as in my prior patent and the fact that the blade was required to remain in constant restraining relation to the associated key to hold the key in supporting engagement with the wedge.

By comparison of the disclosure herein with that shown on Figure 2 of my prior patent herein identified, it will be seen that in my prior patent the amount of radial blade adjustment is limited because if the blade is moved radially outward beyond the key the blade loses restraining relation to the key allowing the key to shift out of supporting engagement with the associated wedge. For this reason, the amount of expensive blade material that may be used in the previously patented cutter is limited by the necessity of maintaining the blade constantly in restraining relation to the key, while in the showing herein, the amount of expensive blade material that may be used is in no sense restricted or limited by the necessity of maintaining the blade in restraining relation to the key, it being observed in this latter connection that after the blade shown herein has been advanced to compensate for wear and grinding it no longer has restraining relation to the key, the shoulder 34 being adequate to hold the key against lateral shifting regardless of the position of the blade.

The new design of blade receiving slot as shown herein, as compared to the cross-sectional form of the blade receiving slot shown in my prior patent, is much simpler requiring fewer operations to produce the slot and simpler and less expensive tools to perform these operations. Thus, the invention disclosed herein marks an advance over the disclosure in my prior patent, herein identified, in the provision of an inserted blade cutter in which the bottom wall of each blade receiving slot is formed immediately at the leading side of the associated blade and approximately in the plane thereof with a substantially right angle, inwardly directed step defining a restraining shoulder in opposed spaced approximately parallel relation to the said leading side wall of the slot and constantly engaging the blade side of the key to inhibit lateral shifting of the key out of supporting relation to the wedge and to a position beneath the blade after the blade has been adjusted outward to a position where a space of a size to receive the key is left between the bottom of the blade and the bottom wall of the slot.

Having thus described the invention what is claimed is:

1. In an inserted blade cutter, a body having a slot provided with front, back and bottom walls, a wedge in the slot and positioned at the front wall thereof, a key in said slot beneath and in pressure relation to the wedge, a blade in said slot and located between the wedge and the back wall of the slot, there being means for the outward adjustment of the blade away from the bottom wall of the slot to a point beyond said key, the bottom wall of the slot being formed with a

shoulder running lengthwise of the key and engaging the blade side of the key at a point between the said front and back walls of the slot and positioned in opposed relation to the front wall of the slot and inhibiting lateral shifting of the key out of supporting relation to the wedge and to a position beneath the blade after the blade has been adjusted outward to a position where a space of a size sufficient to receive a portion of the key is left between the blade and the bottom wall of the slot.

2. In an inserted blade cutter, a body having a slot provided with a bottom wall and side walls, a blade in said slot, a wedge in said slot and located between one of said side walls and the op-

posed side of said blade, a key in said slot beneath and in pressure relation to said wedge and the bottom wall of said slot, there being means for the outward adjustment of the blade away from the bottom wall of the slot to a point beyond said key, the bottom wall of the slot being provided with a restraining shoulder adjacent the blade side of the key for inhibiting lateral shifting of the key out of supporting relation to the wedge and to a position beneath the blade after the blade has been adjusted outward to a position where a space of a size sufficient to receive a portion of the key is left between the blade and the bottom wall of the slot.
